US00D614935S

(12) **United States Design Patent**
Kiraly

(10) **Patent No.:** **US D614,935 S**
(45) **Date of Patent:** ** *May 4, 2010

(54) **SELF CLOSING HINGE**

(75) Inventor: **Dezso Kiraly**, Meadowbank (AU)

(73) Assignee: **D&D Group Pty Ltd**, Frenchs Forest, NSW (AU)

(*) Notice: This patent is subject to a terminal disclaimer.

(**) Term: **14 Years**

(21) Appl. No.: **29/263,733**

(22) Filed: **Jul. 28, 2006**

(30) **Foreign Application Priority Data**

Jan. 31, 2006 (AU) 10311/06

(51) LOC (9) Cl. **08-06**

(52) U.S. Cl. **D8/323**

(58) **Field of Classification Search** ..... D8/323-329, D8/354, 356, 371; 16/221, 234-237, 239-241, 16/245-246, 249, 254, 261, 262, 265, 272, 16/277, 307, 309, 316, 319, 327-330, 335, 16/339, 342, 379, 381-389, DIG. 13, DIG. 40, 16/DIG. 43; 248/200, 221.11, 300, 309.1, 248/317

See application file for complete search history.

(57) **CLAIM**

The ornamental design for a self closing hinge, as shown and described.

DESCRIPTION

FIG. 1 is a front perspective view;

FIG. 2 is a back perspective view;

FIG. 3 is a front view;

FIG. 4 is a back view;

FIG. 5 is a side view;

FIG. 6 is the other side view;

FIG. 7 is a top view; and,

FIG. 8 is a bottom view.

The broken lines in the drawing represent unclaimed environmental material.
